UNITED STATES PATENT OFFICE.

CHARLES H. THURBER, OF BROOKLYN, ASSIGNOR TO THE CELLULOID BRUSH COMPANY, OF NEW YORK, N. Y.

DESIGN FOR THE ORNAMENTATION OF BRUSH-HANDLES.

SPECIFICATION forming part of Design No. 16,100, dated May 19, 1885

Application filed December 1, 1884. Term of patent 3½ years.

To all whom it may concern:

Be it known that I, CHARLES HENRY THURBER, a citizen of the United States of America, and a resident of the city of Brooklyn, in the county of Kings, in the State of New York, have invented a new and original Design for Ornamenting Brushes and Handles of Brushes, Toilet Articles, and Umbrella-Handles, of which the following is a specification.

10 This design is to be applied to handles for brushes, toilet articles, and umbrellas. The handle is elliptical in general contour, with cushioned-shaped projections arranged diagonally with reference to the length of handle, 15 and with small rounded points or buttons placed at the intersections of the depressions, which cross each other at right angles, and thus giving the handle a novel and handsome appearance.

20 Reference is had to the accompanying drawings.

Figure 1 shows a plan view of a handle incorporating my design; Fig. 2, my design as applied to handle of hair-brush; Fig. 3, a 25 transverse section of the same on the line C C, and Fig. 4 a longitudinal section on the line E E.

Referring to the drawings, *a* refers to the body of the handle, *b* the cushioned-shaped 30 projection arranged diagonally with reference to the length of the handle, and *d d* the small rounded points or buttons which are placed

at each intersection of the depressions, crossing each other at right angles. The body of the handle is elliptical in cross-section, and the 35 outer end portion is of the same proportion as the attaching end. The sides and edges taper in outline from the center to both ends on similar curves.

I claim—

1. A design for the ornamentation of brush-handles and similar articles herein shown and described, the same consisting of a handle having rounded or cushioned-formed projections set in diagonal lines upon the handle, the 45 depressions between said projections crossing each other at right angles. 40

2. A design for the ornamentation of brush-handles and similar articles herein shown and described, the same consisting of a handle having rounded or cushioned-formed projections set in diagonal lines upon the handle, and with small rounded points or buttons placed at the intersections of the depressions, which cross each other at right angles. 50

In testimony that I claim the foregoing as my invention I have signed my name, in presence of two witnesses, this 26th day of November, 1884.

CHAS. H. THURBER.

Witnesses:

JAS. H. HOWELL,
W. O. MERRILL.
